UNITED STATES PATENT OFFICE

WILLIAM S. KING, OF WINNETKA, ILLINOIS

ILLUSTRATIVE CHART

Application filed March 8, 1929. Serial No. 345,403.

My invention relates to a chart including a representation of an altar such as is used for example in a Roman Catholic church, the chart being adaptable for use in demonstrating or teaching, for example to children, the movements of the Mass. One object of my invention is to provide such a chart which shall include a representation of the altar and which shall have associated with it means for supporting the figures of priests and acolytes and of the various objects employed in the Mass. Other objects will appear from time to time in the course of the specification and claims.

I illustrate my invention more or less diagrammatically in the accompanying drawings, wherein—

Figure 1 is a front elevation of the chart; Figure 2 is a section on the line 2—2 of

Figure 1;

Figure 3 is a section on the line 3—3 of Figure 1; and

Figure 4 is a section on the line 4—4 of Figure 1.

Like parts are indicated by like symbols throughout the specification and drawings.

A generally indicates any suitable back or body member which may be made, for example, of flat sheet metal. It may be hung on a wall for example by employment of the holes or eyelets A¹.

Painted, stamped, or indicated in any suitable manner on the face of the chart is a representation of the altar which may include for example an altar proper B, reredos B¹, tabernacle B², crucifix B³, and candelabra B⁴. The altar steps are indicated as at B⁵.

In order to support the figures I may employ any suitable means whereby the figures employed may be positioned upon the chart. I illustrate, however, a plurality of ledges or shelves or channels into which the figures may be inserted. Taking as a typical channel the lower channel member C, as shown in Figures 1 and 3, is the supporting channel which represents the floor level of the church. This channel C may be riveted or otherwise secured to the chart body as at C¹ and includes a rear side member C², a shorter or lower forward member C³ and a connecting

bottom member C⁴. If desired a spring or securing member C⁵ may be employed, also riveted as at C¹ and extending downwardly and forwardly toward the member C³. This member has importance in view of the fact that a number of the channels are vertically aligned, as shown in Figures 1 and 3. Thus in the channel member next above, C⁶, the forward member C⁷ may lie in the general plane of the member C⁵. In turn the channel C⁸ next above has a forward member C⁹ lying in the general plane of the securing member C¹⁰ of the channel C⁶. If desired the topmost member may be a simple channel, as shown at C¹¹. As to the individual channels any arrangement may be employed which suitably represents a typical ecclesiastical structure. However, for purposes of illustration C may be indicated as representing the floor level and the channels C⁶, C⁸ and C¹¹ the various higher steps or levels about the altar.

In order to support the objects employed in the celebration of the Mass and positioned upon the altar itself I may employ the shelves or channels D, D¹ the lower of them having the securing member D² as shown in Figure 2.

If desired I may position at either side of the altar, as in the channels D³ any suitable descriptive or illustrative material or notices.

Whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

The invention involves as a basis a chart or representation of an altar and of the steps leading up to the altar, representing an altar at which the Mass is celebrated. The purpose of the chart is to instruct in the order of the Mass, or to give instruction in the order of movements taken by the celebrants. In general it serves to instruct those to whom the details are unfamiliar or have become

vague, and is particularly useful in the instruction of children.

The base member A may be of metal or any other suitable material and carries a pictured representation of the altar. Mounted upon the base are supporting angles or shelves above described, or their equivalents, which are positioned at the various levels at which the priests or acolytes might stand, other shelves or angles being positioned at the top of the altar. In employing the chart figures are used which may represent priest and acolyte and the various objects employed in the Mass. Inasmuch as the appearance of priest and acolyte and of the various objects is familiar they are not represented in the present drawings in detail but it will be understood that in demonstrating the simple Mass, for example, the figures of a priest and an acolyte may be employed; whereas for the celebration of a solemn high Mass other figures may be employed representing deacon and sub-deacon, for example. Also figures representing the altar guards may be employed, or the chalice, paten, burse, etc. It will be understood that the instructor, in employing the chart, will position the various figures employed at points on the chart corresponding to the places occupied in the actual celebration of the Mass. As the figures are freely movable their successive positions in the course of the celebration can be easily demonstrated.

I claim:

- 35 1. As a new article of manufacture, a chart for ecclesiastical instruction which comprises a base having thereon a representation of an altar, a plurality of supporting elements mounted at different levels, the supporting portions being in different planes and adapted to receive figures representing the celebrant or celebrants of Mass and the objects employed in the celebration of the Mass.
- 40 2. A chart for ecclesiastical instruction, including a base having thereon the representation of an altar, supporting means positioned on the face of said chart and a plurality of figures, representing celebrants of Mass and the objects employed in celebration of the Mass, such figures being movably mounted upon said supporting means, said supporting means being adapted removably to receive said figures at any point throughout the length thereof.
- 45 3. A chart for ecclesiastical instruction, including a base having thereon the representation of an altar including steps, supporting means positioned on the face of said chart at levels corresponding to the various levels of said steps, and a plurality of figures, representing the celebrants of Mass, and the objects employed in the celebration of Mass, such figures being movably mounted upon said supporting means.
- 50 4. A chart for ecclesiastical instruction,

which includes a base having thereon the representation of an altar, supporting means positioned on the face of said chart at points corresponding to the various levels about the altar, a plurality of figures, representing the celebrants of Mass, movably supported by said supporting means and removable therefrom at any point throughout its length, additional supporting means located to correspond to the altar top, and figures representing objects employed in the celebration of Mass, adapted to be position removably upon said additional supporting means.

5. A chart for ecclesiastical instruction, including a base having thereon the representation of an altar, supporting means positioned on the face of said chart at levels corresponding to the various levels about said altar, and a plurality of figures, representing the celebrants of Mass, and the objects employed in the celebration of Mass, such figures being movably mounted upon said supporting means, each of said supporting means extending outwardly from the face of the chart beyond the supporting means next above for a distance sufficient to permit figures to extend upwardly beyond the supporting means next above without interference therewith.

6. A chart for ritualistic instruction, including a base having thereon the representation of an altar having different levels, supporting means positioned on the face of said charts at levels corresponding to the various levels about said altar, a plurality of figures supported upon said supporting means, each of said supporting means extending outwardly from the face of the chart beyond the supporting means next above to permit the figures at each level to be moved without interfering with figures at the remaining levels, some of the supporting members supporting the figure at the next lower level from lateral flexure.

Signed at Chicago, county of Cook, and State of Illinois, this 13th day of February, 1928.

WILLIAM S. KING.
